UNITED STATES PATENT OFFICE

2,500,640

CRIB ATTACHMENT

Robert William Lord, Portsmouth, N. H.

Application September 24, 1946, Serial No. 698,967

5 Claims. (Cl. 5—100)

1

This invention relates to cribs having drop sides, the primary object of the invention being to provide means for securing the usual drop side latch mechanism of a crib, against movement, except when operated from a point externally of the crib.

An important object of the invention is to provide an attachment of this character which may be readily attached to cribs having the usual drop sides, without the necessity of making extensive alterations in the crib structure, in order to mount the device.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

Referring to the drawings:

Figure 1 is a side elevational view of a crib, showing an attachment constructed in accordance with the invention, as mounted thereon.

Figure 2 is a sectional view taken on line 2—2 of Figure 1.

Figure 3 is an enlarged plan view of the attachment, the side rail to which the attachment is secured, being shown in dotted lines.

Figure 4 is an enlarged elevational view illustrating one edge of the latch and showing its relative position with respect to the usual pivoted latch arm of a drop-leaf crib.

Referring to the drawings in detail, the crib comprises the usual end sections which include vertical rods 5 on which the side members 6 of the crib, slide.

Reference character 7 indicates one of the side rails of the crib, and the reference character 8 indicates the lower rail of the drop side of the crib. Secured to the lower rail 8, are the rods 9 which have their ends 10, extended at right angles with respect to the main portions of the rods, the right-angled ends being designed to move against the vertical rods 5 and secure the drop sides of the crib in their elevated positions.

The rods 9 are operated by means of the lever 11 which is normally held to its outermost position, by means of the springs 12. In order to operate the rods 9, it is necessary to move the lever 11 inwardly, against the action of the springs 12, whereupon the rods 9 are rotated, moving the right-angled ends thereof out of engagement with the rods 5, releasing the drop sides for vertical movement.

The latch member forming the subject matter of the present invention, is pivotally mounted to the side rail 7, and includes a wide plate 13 formed with an arm 14 that extends therefrom,

2

the arm 14 having an upstanding ear 15 adapted to normally rest against the side of the side rail 7 on which it is secured, as clearly shown by Figure 2 of the drawings. The finger piece indicated at 16, is formed at the free end of the arm 14, and since the arm 14 is constructed of semi-rigid metal, it will be seen that the arm 14 may be swung downwardly to the dotted line position as shown by Figure 4 of the drawings, whereupon the ear 15 will move to a point below the lower edge of the side rail 7. The latch member may now be swung inwardly to the dotted line position as shown by Figure 3 of the drawings.

Extending laterally from the plate 13, is a flange 17 that is adapted to move against one edge of the lever 11, providing a stop to prevent the plate, forming the latch, from being moved too far when the arm is swung outwardly to lock the latch lever 14 against movement.

One edge of the plate 13 is extended downwardly at right angles providing a wide flange 18 against which the lever 11 engages.

From the foregoing it will be seen that when the latch forming the subject matter of the present invention, is moved to the position as shown by Figure 2 of the drawings, the lever 11 of the usual drop side latch, is engaged by the flange 18, and it is impossible to force the lever 11 inwardly to operate the latch and lower the drop side of the crib.

When it is desired to lower a side of the crib, it will be necessary to move the arm 14 downwardly to the dotted line position as shown by Figure 4 of the drawings. The arm 14 may now be swung inwardly away from the lever 11, and the lever 11 may now be operated to move the securing rods of the drop side to their inactive positions, releasing the drop sides for downward movement.

What is claimed is:

1. The combination with the pivoted latch of a crib having vertically movable sides, of a latch securing device, comprising a pivoted arm secured to the crib and adapted to move into engagement with said pivoted latch of the crib, securing said latch and the side of the crib, against movement.

2. The combination with the pivoted latch of the side latching member of the crib, of a latch securing device comprising a pivoted arm secured to the crib adapted to swing to a position into engagement with the latch, restricting movement of the latch, and means for securing the pivoted arm against movement to release the latch.

3. The combination with the pivoted latch of a crib side securing means, of a latch securing device comprising an arm pivotally secured to the crib, said arm adapted to swing to a position in

contact with the inner surface of the latch, an ear rising from the arm adapted to engage the crib, securing the arm against movement, and said arm adapted to bend downwardly, releasing the ear, whereby pivotal movement of the arm is permitted to release the latch.

4. The combination with the pivoted latch of a crib side member holding means of a latch securing member comprising an arm pivotally connected to the bottom of the crib, one end of the arm being formed with a finger piece and adapted to bend downwardly, a flange rising from the arm and adapted to engage the crib, securing the arm against pivotal movement, and a plate forming an extension of the arm securing device, adapted to engage the latch, securing the latch against movement.

5. The combination with the pivoted latch of a crib having movable sides, of a latch securing device comprising a wide plate, pivotally mounted on the crib, a flange rising from the plate and adapted to engage the crib, restricting pivotal movement of the plate in a horizontal plane, a flange formed at the free end of the plate and

adapted to engage the latch, securing the latch against movement, an arm extending from the plate and having a finger piece at its outer end, said arm adapted to swing downwardly disengaging the flange of the plate from the crib, whereby pivotal movement to disengage the plate and latch member is permitted.

ROBERT WILLIAM LORD.
